UNITED STATES PATENT OFFICE.

HARRY RALPH RICARDO, OF LONDON, ENGLAND.

VALVE GEAR FOR INTERNAL-COMBUSTION ENGINES.

Application filed April 1, 1919. Serial No. 286,693.

To all whom it may concern:

Be it known that I, HARRY RALPH RICARDO, a subject of the King of England, residing in London, England, have invented certain new and useful Improvements in Valve Gears for Internal-Combustion Engines, of which the following is a specification.

This invention relates to valve gear for internal combustion engines of the high speed type having overhead valves and twin cylinders the pistons in which are connected to one and the same crank pin and has for its object to enable the valves to be operated silently and by means of simple mechanism which permits the various parts to be accessible.

According to this invention two rocking levers are mounted on the twin cylinder heads so as to act on tappet levers and through them operate both inlet and both exhaust valves and these levers are rocked by means of eccentrics mounted on the shaft driven by gearing from the engine crank shaft. Four tappet levers are provided each tappet lever actuating either an inlet or an exhaust valve and all these levers are loosely carried on one or more rock shafts mounted on the cylinder heads. The two rocking levers are carried on a second rock shaft and an arm of each rocking lever actuates alternately an arm of each of two tappet levers these engaging arms acting as wipers. The shaft on which the eccentrics are mounted is disposed transversely to the engine crank shaft and the gearing by which this shaft is driven from the crank shaft is arranged in some convenient manner.

The invention may be put into practice in various ways but the accompanying drawings illustrate by way of example one construction of the improved valve gear as applied to a twin cylinder engine the pistons in which are connected to a single long crank pin. In these drawings,

Figure 1 is an elevation of the engine partly in vertical section showing the improved valve gear.

Figure 2 is a plan of the heads of the cylinders showing the rock shafts and levers mounted thereon.

Like letters indicate like parts throughout the drawings.

The cylinders A and A' are disposed side by side and the pistons B B' therein are

connected to a single crank pin C on the crank shaft D. Inlet and exhaust valves are mounted side by side in the heads of the two cylinders and the valve spindles are carried upwards parallel to each other and disposed on either side of a rock shaft E suitably carried in bearings on the cylinder heads. Above and parallel to this shaft E and a suitable distance therefrom is carried a second shaft F. Loosely mounted on the shaft E are two laterally projecting levers G G' each of which has a second and upwardly directed arm G². On the shaft F are loosely mounted four laterally projecting levers H H' and J J' and the end of each of these levers lies over the end of a valve spindle K K'. Each lever H H' has a second and downwardly directed arm H² while each lever J J' has a similarly downwardly directed arm J². The arms H² J² of the levers H and J lie on either side of and in contact with the sides of the arm G² of the lever G while the arms H² J² of the levers H' and J' are similarly positioned with respect to the arm G² of the lever G'. The arrangement is such that as the lever G or G' is oscillated the arm G² of that lever will act either on the lever arm H² or the lever arm J² with a wiper action and as a result the levers H H' and J J' will be turned and caused to act on the valves K K'.

On the crank shaft D is a skew toothed wheel D' which gears with a corresponding toothed wheel L mounted on a shaft L' disposed transversely with respect to the crank shaft D. The shaft L' carries two eccentrics M and N. A rod M' transmits motion from the eccentric M to the rocking lever G while a similar rod N' transmits motion from the eccentric N to the rocking lever G'. Thus as the shaft L' is rotated the levers G and G' are rocked and the valves K and K' are actuated through the tappet levers H H' and J J'.

The engine conveniently works on the four stroke cycle and the timing is so arranged that firing occurs alternately in the cylinders A and A' thus giving an impulse at each revolution. It thus becomes possible with the single lever G to operate both the inlet valves through the tappet levers H and J while the single lever G' operates both exhaust valves through the tappet levers H' and J'. Each lever G and G' on

- its upward stroke operates one valve and the other valve on its downward stroke. If inlet valves of the "masked" type are used, that is to say a valve such as described in 5 the specification of the present inventor's prior application for British Letters Patent No. 14,628/16, filed 14th October, 1916, both the levers G and G' can be made identical as also the eccentrics M and N and 10 their rods M' and N' while further the tappet levers H H' and J J' can all be formed similar. Hence the whole valve gear can be so constructed that the parts are interchangeable.
- 15 The shaft L' can be utilized to drive the magneto, oil pumps and other auxiliary parts.
- The detail construction and disposition of 20 the valve gear may be modified to suit the formation of the engine to which it is applied.
- 25 In place of the tappet levers H H', J J' being all mounted on one and the same rock shaft F it is in some cases preferable to provide two separate rock shafts suitably mounted, one shaft carrying the tappet levers H and J while the other shaft carries the levers H' and J'. Such an arrangement to some extent simplifies the construction and arrangement of the tappet levers.
- 30 What I claim as my invention and desire to secure by Letters Patent is:—
1. Mechanism for operating internal combustion engine valves of the poppet type 35 including two tappet levers mounted to oscillate independently about an axis intermediate the stems of the poppet valves, each tappet lever having an arm for engaging a valve stem and a second arm at an angle thereto, each of said second arms being provided with a bearing surface, the two such bearing surfaces facing in opposite directions, and a lever mounted to oscillate about an axis parallel to the axis of the tappet 40 levers, said lever having a wiper arm provided with two oppositely facing bearing surfaces to engage the bearing surfaces of the tappet levers respectively, the bearing surfaces of the wiper arm being spaced apart a distance only slightly less than the 45 normal distance between the opposed bearing surfaces of the tappet levers, whereby
- 50 sounds of impact of the wiper arm on the tappet levers are minimized.
2. Mechanism for operating internal combustion engine valves of the poppet type 55 including two tappet levers mounted to oscillate independently about an axis intermediate the stems of two poppet valves, each tappet lever having an arm for engaging a valve stem and a second arm at an angle thereto, each of said second arms being provided with an elongated bearing surface, the two such bearing surfaces facing in opposite directions, and a lever mounted to 60 oscillate about an axis parallel to the axis of the tappet levers, said lever having an elongated wiper arm occupying substantially the entire space between the bearing surfaces of the tappet levers and having elongated bearing surfaces substantially coextensive with and lying closely adjacent the corresponding bearing surfaces of the tappet levers, whereby sounds of impact of the 65 wiper arm on the tappet levers are minimized.
3. In a valve gear for a high speed internal combustion engine having overhead valves the combination of two cylinders, a 70 crank shaft on which act the pistons in these two cylinders, inlet and exhaust valves in the heads of these cylinders, four tappet levers mounted on the cylinder heads so as to rock about a common axis and adapted to operate respectively both inlet 75 and both exhaust valves, a wiper arm formed integral with each tappet lever, two levers mounted on the cylinder heads so as to rock about a common axis which is parallel to the fulcrum axis of the tappet 80 levers, each of these rocking levers having a wiper arm adapted to engage the wiper arms of two tappet levers, one pair of said tappet levers operating both inlet valves and the other pair both outlet valves, two eccentrics mounted on a shaft which is disposed transversely to the engine crank shaft, rods connecting these eccentrics respectively to the two rocking levers, and gearing between the crank shaft and the transverse 85 shaft as set forth.
- In testimony whereof I have signed my name to the specification.
- HARRY RALPH RICARDO.
